UNITED STATES PATENT OFFICE.

MARTIN McHALE, OF ANYOX, BRITISH COLUMBIA, CANADA.

DOLLY-HAMMER CYLINDER FRONT HEAD.

Application filed September 18, 1923. Serial No. 663,438.

To all whom it may concern:

Be it known that I, MARTIN McHALE, a citizen of Canada, and a resident of Anyox, in the Province of British Columbia and 5 Dominion of Canada, have invented a new and Improved Dolly-Hammer Cylinder Front Head, of which the following is a full, clear, and exact description.

This invention has relation to drill sharpeners and has particular reference to an improvement in a dolly hammer cylinder front head which is particularly designed for use in connection with a "Model 8 Waugh" drill sharpener although the same is not necessarily restricted to use in connection with this machine.

At the present time the cylinder front head in which the dollies are mounted for rapid reciprocation are provided with no 10 means for compensating for the wear on the shanks of the dollies or on the bearing surfaces with which they contact and it thus follows that after a limited time the dolly boxes or retainers become so badly worn 15 that they must be replaced at a greater expense.

It is, therefore, the principal object of the present invention to provide a front head which includes means for compensating for 20 the wear on the dolly shank and its bearing in order to increase both the length of life 25 of the dollies and the bearings.

As a further object the invention contemplates more specifically a dolly hammer cylinder front head which is provided with a separate shoe or bearing block upon which the shank of the dolly rests and moves in order to prevent wear on the main body of 30 the front head whereby the shoe or bearing 35 block when worn may be replaced at a very small expense.

As a still further object the invention contemplates a dolly hammer cylinder front head which is provided with a cover and 40 means for retaining the same in covering relation, which means facilitates the introduction to or removal of the dollies from the front head.

As a still further object the invention contemplates a dolly hammer cylinder front head which is comparatively simple in its construction, inexpensive to manufacture and which is readily applicable to or removable from the dolly hammer cylinder.

With the above recited and other objects in view, the invention resides in the novel

construction set forth in the following specification, particularly pointed out in the appended claims and illustrated in the accompanying drawings, it being understood that 60 the right is reserved to embodiments other than those actually illustrated herein to the full extent indicated by the general meaning of the terms in which the claims are expressed.

65 In the drawings—

Figure 1 is a fragmentary side elevation of a drill sharpening machine with the dolly hammer cylinder front head constructed in accordance with the invention applied thereto, parts being broken away to disclose the underlying structure;

Fig. 2 is an enlarged longitudinal sectional view through the front head;

Fig. 3 is an enlarged plan view thereof;

And Fig. 4 is a transverse sectional view taken approximately on the line 4—4 of Fig. 2.

Referring to the drawings by characters of reference, A designates the base of the 80 machine, B the lower die block, C the bit forming die having a bore D for receiving the bit. The dolly hammer cylinder E has mounted therein the dolly hammer F, to which cylinder fluid under pressure is admitted for actuating the hammer to coat 85 with the dolly G.

The front head which constitutes the invention in the present case comprises a substantially box-like body 10 which is open 90 at its upper side and is provided with a bottom 11, parallel side walls 12 and 13, a front end wall 14 and a rear end wall 15. The body is provided with a rearward tubular extension 16 which is provided with an outer 95 axial enlarged bore 17 for receiving therein the forward end of the dolly hammer cylinder E, the said extension being provided with lateral apertured ears 18 for alignment with similar ears H on the dolly hammer 100 cylinder E to receive therethrough clamping bolts 19 for attaching the front head to the cylinder. The extension 16 is further provided with an inner reduced bore 20 communicating with the bore 17 and through which the forward end of the hammer F is movable into engagement with the collar I at the rear end of the dolly shank J. The front and rear end walls 14 and 15 of the front head body 10 are provided with substantially semi-circular recesses 21, the recess 110 in the rear wall communicating with the in-

2

ner bore 20 and said recess being of slightly lesser diameter than the bore 20 to provide a stop shoulder 22 for arresting or limiting the forward movement of the dolly by the engagement of the collar I therewith. Within the lower end of the body 10 a laterally movable wedge block 23 is arranged, which block is of an appropriate length to snugly fit between the ends walls 14 and 15, while the same is of lesser width than the distance between the side walls 12 and 13. A bearing block or shoe 24 of a length and width to snugly fit between the side walls 12 and 13 and end walls 14 and 15 is arranged within the body 10, the same being provided with a laterally inclined lower wedge face 25 which cooperates with a complementary laterally inclined upper wedge face 26 on the wedge block 23. The bearing block or shoe 24 is provided with a substantially semi-circular bearing recess 27 in its upper face within which the shank J of the dolly G is mounted. The body 10 is provided with laterally projecting bosses 28 adjacent the lower portion of the side walls 12 and 13 and said bosses are provided with threaded bores 29 which communicate with the interior of the body 10 and receive therethrough the threaded shanks 30 of adjusting screws 31, the inner ends of which screws engage respectively with the opposite sides of the wedge block 23 for moving or sliding the same laterally to effect through the cooperating wedge faces 25 and 26 the raising and lowering of the bearing block or shoe 24. Lock nuts 32 are threadedly arranged on the shanks 30 for retaining the adjusting screws in adjusted position. The improved front head further includes a cover 33 which is adapted when in closed position to rest upon the upper open end of the body 10 for holding the dolly shank J in the bearing recess 27 of the bearing block 24 and for co-operating with the flattened side K of the dolly shank to prevent rotary movement thereof. As illustrated the cover 33 is swiveled to the lower end of a clamp screw 34 by virtue of a pin 35 intersecting the circumferential groove 36 in the lower end of the clamp screw 34. The clamp screw 34 extends through the internally threaded nut 37 in a cross-bar 38 which is hingedly connected adjacent one end by a hinge pin 39 to the spaced hinge knuckles 40 projecting upwardly from the side wall 12 of the body 10. At its opposite free end the cross-bar 38 has hinged thereto by a hinge pin 41 a bail 42, the bight 43 of which is engageable under a keeper lug 44. The cover 33 is provided with laterally projecting ears 45, one of which is engageable between the spaced hinge knuckles 40 and the other of which is received between the furcations 46 at the bifurcated upper end of the keeper

44. The inner end of the tubular extension 16 is cut away on its upper side at 47 and the rear or inner end of the cover 33 extends into the cut-away portion and is provided with an arcuate recess 48 which completes the bore 20 when the cover is closed, but partially opens the same when the cover is open to allow for the removal of the collar I. The cover 33 is provided with an opening 49 for the introduction of oil to the interior of the front head. The crossbar is provided with a tail 50 which projects from the hinged end 39, which tail engages with the side wall 12 to limit the swinging of the cover and crossbar in the open position. The dolly is provided with the usual enlarged head L at its forward end which produces a shoulder M at its juncture with the shank J, which shoulder coacts with the front end wall 14 and prevents engagement of the shoulder with the shoe or bearing block 24. The bottom wall 11 of the body 10 is provided with an opening 51 through which a tool may be inserted for forcing the wedge block and bearing block or shoe from within the body when it is desired to remove the same.

In practice, when the shank J of the dolly and the bearing recess 27 of the bearing shoe become worn, the adjusting screw 31 extending through the wall 12 is unscrewed and at the same time the opposite adjusting screw 31 extending through the wall 13 is screwed up to move the wedge block 23 toward the left in Fig. 4. This will effect a raising of the bearing block 24 and a consequent compensation for the wear. When it is desired to open the cover 33 for the purpose of removing the dolly or bearing block 24, the clamp screw 34 is turned in the nut 37 of the cross-bar in a direction to move the free end of the crossbar and bail 42 downwardly whereby the bight 43 may be disengaged from the keeper lug 44. The operator may then swing the cross bar on its hinge pin 39 upwardly to lift the cover from its covering position thereby permitting of the removal of the dolly and the bearing block or shoe 24. By means of the adjusting screws 31 any degree of looseness or tightness of fit of the dolly may be accomplished. It will be noted that in the present instance no springs or other means are employed for returning the dolly after it has struck the blow on the face of the drill bit, as it has been found in actual practice that there is no need for such means due to the fact that the rebound or recoil of the dolly is sufficient for returning the same to deliver the next blow. As a matter of fact it has been found that devices for returning the dolly only tend to retard the effect of the blow delivered by the dolly hammer on the dolly.

While the device has been illustrated and primarily designed for use in connection

with the "Model 8 Waugh" drill sharpener it is, of course, understood that slight variations in the shape, size, and construction may be made to render the device applicable 5 to various other machines of this character without in any way departing from the spirit of the invention.

I claim:

1. In a drill bit sharpening machine employing a dolly having a head at its outer end and a collar at its inner end, a cylinder front head including a box-like body having side walls and front and rear walls forming between them a bearing cavity and of which 10 the front and rear walls are respectively engageable by the head and collar of the dolly, a bearing member for the dolly disposed in the cavity and extending in use slightly above the front and rear walls and protected 15 by the latter from the dolly head and collar, having an inclined lower face, a wedge shift- 20 able laterally in the base of the cavity and extending from the front to the rear walls thereof, adjusting means for adjusting said 25 wedge and securing the same in adjusting position, and a cover extending across and secured against the upper edges of the side walls of the body.
2. In a drill bit sharpening machine employing a dolly having a head at its outer end and a collar at its inner end, a cylinder front head including a box-like body having side walls and front and rear walls forming between them a bearing cavity and to which 30 the front and rear walls are respectively engageable by the head and collar of the dolly, a bearing member for the dolly disposed in the cavity and extending in use slightly above the front and rear walls and protected 35 by the latter from the dolly head and collar, having an inclined lower face, a wedge shift- 40 able laterally in the base of the cavity and extending from the front to the rear walls thereof, adjusting means for adjusting said 45 wedge and securing the same in adjusting position, and a cover extending across and secured against the upper edges of the side walls of the body, said cover having a flat end surface and said dolly having a flattened

upper portion cooperating with the lower 50 surface of the cover to prevent rotation of the dolly in use.

3. In a drill bit sharpening machine employing a dolly having a head at its outer end and a collar at its inner end, a cylinder 55 front head including a box-like body having side walls and front and rear walls forming between them a bearing cavity and to which the front and rear walls are respectively engageable by the head and collar of the dolly, 60 a bearing member for the dolly disposed in the cavity and extending in use slightly above the front and rear walls and protected by the latter from the dolly head and collar, having an inclined lower face, a wedge shift- 65 able laterally in the base of the cavity and extending from the front to the rear walls thereof, adjusting means for adjusting said wedge and securing the same in adjusting position, and a cover extending across and 70 secured against the upper edges of the side walls of the body, said cover having an oil opening therethrough and means for clamping the cover in place including an upper cross-bar in movable engagement with the 75 body and a clamping screw threaded through the cross-bar and having a swiveled connection centrally of the cover.

4. In a drill bit sharpening machine, a dolly having a head and a collar at its opposite ends a dolly hammer cylinder front head, an adjustable and removable bearing for the dolly mounted in the front head, means for effecting adjustments of said bearing to compensate for wear thereon and on 80 the dolly, said means comprising a wedge block, interengaging wedge faces on the bearing and wedge block, devices for operatively moving the wedge block to obtain said adjustments, and guide means for the bearing 85 provided on the front head body, certain of said guide means constituting stops for engagement with the head and collar of the dolly for limiting the movement of the dolly 90 whereby to prevent engagement of the same 95 with the bearing.

MARTIN McHALE.
